UNITED STATES PATENT OFFICE

TIMOTHY CLARK WARDLEY, OF ELORA, ONTARIO, CANADA, ASSIGNOR TO T. E. BISSELL COMPANY LIMITED, OF ELORA, ONTARIO, CANADA, A CORPORATION OF CANADA

DISK HARROW

Application filed September 17, 1930. Serial No. 482,587.

The object of this invention is to devise a disk harrow for the cultivation of cotton, corn, and other crops planted in drills or rows which will simultaneously disk out the roots of the preceding crop, level the previously formed drills and make new drills for the succeeding crop and cover the roots of the preceding crop.

In carrying out this object the harrow comprises several separate or individual groups of disk gangs flexibly connected in tandem, means for adjusting the disk gangs to alter the cutting angles of the groups and means for adjusting the inclination of the disk gangs to the surface of the land and maintaining the inclined adjustment for making the new drills.

For an understanding of the invention reference is to be had to the following description and to the accompanying drawings in which:

Fig. 1 is a plan view of a disk harrow comprising two groups of disk gangs flexibly coupled in tandem;

Fig. 2 is a side elevation of the harrow shown in Fig. 1;

Fig. 3 is a plan view of a center frame and a plurality of groups of disk gangs connected to it capable of simultaneously forming four drills;

Fig. 4 is a plan view of the leading group of disk gangs shown in Fig. 1;

Fig. 5 is a side elevation of the group shown in Fig. 4;

Fig. 6 is a perspective view of a disk gang;

Fig. 7 is a plan view of the construction shown in Fig. 6;

Fig. 8 is a plan view of two disk gangs;

Fig. 9 is a sectional view on the line 9—9 of Fig. 4;

Fig. 10 is a sectional view on the line 10—10 of Fig. 4;

Fig. 11 is a fragmentary detail of a beam for one of the groups showing the center frame in section and a guide embracing it for maintaining each pair of disk gangs constituting the group in its spaced relation to the other pair of the same group and permitting the two pairs to undulate independently of each other; and

Fig. 12 is a perspective view of one of the axle bearings.

Like characters of reference refer to like parts throughout the specification and drawings.

The harrow, designed to disk out and cover the roots of a preceding crop, level the previously formed drills in which these roots were planted, and form a new drill for the succeeding crop, comprises a plurality of disk gangs arranged in several individual or separate groups flexibly connected in tandem.

Each disk gang of each group is composed of an axle 4, several disks 5, a bearing 6 between the two outermost disks and a bearing 7 beyond the innermost disk. Each bearing 6 is formed with an elliptical hole 6a in which is entered the corresponding journal of its respective beam and this elliptical hole permits of the disk gang being vertically inclined relatively to the surface over which the harrow is moving independently of any corresponding movement of the beam. The leading group is composed of a center frame 2 and a pair of disk gangs 1, 1a coupled together by a beam 1b provided with journals 1c entered in the outer bearings 6, and two stays or rods 8 and 10 extending forwardly from the beam 1b and connected at their forward ends with the center frame 2. The center frame extends lengthwise of the harrow and is provided at its forward end with a coupling 3 for connecting the harrow to a tractor or other draft apparatus and at its rear end with a coupling 3a for connecting it to the center frame 14 of the following group.

In advance of the disk gangs 1, 1a is a toothed segment 12 and fulcrumed to the center frame is a lever 13 having a spring tensioned dog 13a engaging with the teeth of the segment. Connected with the lever 13 and to the inner bearings 7 of the disk gangs 1, 1a are rods 15, 15a for adjusting the disk gangs to alter the cutting angles of the group.

Extending from each rod 15, 15a vertically above the inner end of each disk gang 1, 1a is a pressure arm 16 for contacting the beam 100

1b and depressing the inner end of the gang to maintain a uniform depth of cut while these gangs are tearing out the roots of the preceding crop and levelling two previously formed drills.

5 formed drills.

The following group of disk gangs comprises a center frame 14 extending lengthwise of the harrow and provided with a coupling 21 at its forward end by which it can be connected to the rear end of the center frame 2, and four disk gangs arranged in two pairs 17, 17a located one at each side of the center frame for simultaneously forming two new drills. The disk gangs of the pair 17 are provided with a frame composed of a beam 17d having journals 1c entered in the outer bearings 6 of the two gangs and draw-bars 17e extending forwardly from the beam and rigidly connected to the center frame.

10 14 in advance of the disk gangs of the pair 17 for their undulation with the center frame.

15

20

The disk gangs of the pair 17a are provided with a frame composed of a beam 17f having journals entered in the outer bearings 25 of the gangs and two drawbars 17e extending forwardly from the beam and rockably connected to the center frame 14, in advance of the disk gangs of the pair 17a. The inner end of the beam 17f is provided with a forked guide 17g which embraces the center frame 14, maintains the pair 17a in its spaced relation to, and permits of its undulating movement independently of, the center frame 30 and other pair 17.

35 Extending forwardly from each beam to the outer one of its drawbars is a brace 17k on which is mounted a toothed segment 17m and an adjusting lever 17h connected by rods 30 with the inner bearings 7 for the adjustment of the cutting angles of the disk gangs. The beam of each pair 17, 17a is provided with two arms 26 one above the inner bearing of each gang, and lengthwise adjustable on each arm is a clip 26b having a forked 40 member 26c. A flexible suspender 26a is connected to each of the rods 30 adjacent to the inner bearings 7 and adjustably entered through the forked member 26c for suspending the inner end of the gang from the arm 45 26 and varying its inclination to the surface of the land when forming the new drills and covering the roots of the preceding crop. 50

In Fig. 3 are shown four pairs of disk gangs arranged in two groups for simultaneously forming four drills or rows, each group being provided with a center frame 14 flexibly connected at the front to a draft attachment 40 and at the rear to a coupling bar 41.

60 The disk gangs 1, 1a are rigidly connected to the center frame 2 and spaced from each other for simultaneously levelling two previously formed drills and tearing out the roots of the previous crop. The disk gangs of the pair 17 follow the disk gang 1 and the disk 65 gangs of the pair 17a follow the disk gang 1a

for covering the roots torn out by the gangs 1, 1a and simultaneously forming two new drills, the height of which is determined by the height to which the inner bearings 7 are raised, the raising of the bearings being effected by the adjustment of the flexible suspenders 26a through the forked members 26c and the lengthwise adjustment of the clips 26b on the arms 26. For instance if the flexible suspenders are so adjusted through the forked members 26c that the axles of the gangs are parallel with the beam, the disks only operate to cut the soil. If on the other hand the suspenders are adjusted to raise the inner bearings to the level of the arms 26 the disks 5 bank up the soil at each side of the drill to its maximum height. 70 75 80

Having thus fully described my invention what I claim as new and desire to secure by Letters Patent is:—

1. A disk harrow comprising a center frame; a beam having a journal at each end; two disk gangs each provided with an axle having a bearing adjacent to its outer end in which one of the journals is entered for pivotally connecting the disk gang to the beam, and a bearing adjacent to its inner end; levers connected with the bearings adjacent to the inner ends of the axle for adjusting the cutting angles of the disk gangs and flexible suspenders connected with the same bearings and adjustably connected with the beam for vertically inclining each disk gang relatively to the land and maintaining it in its inclined position. 100

2. A disk harrow as claimed in claim 1 having an arm extending from the beam above each disk gang to which the flexible suspender is adjustably connected for inclining the disk gang relatively to the land. 105

3. In a disk harrow a center frame arranged lengthwise of the harrow; a beam having a journal at each end, two disk gangs located one at each side of the center frame, and provided with an axle having a bearing adjacent to its outer end in which one of the journals is entered for pivotally connecting the disk gang to the beam and a bearing at its inner end beyond the disks, a lever, a toothed segment, and rods connecting the lever with the bearings at the inner ends of the axles for adjusting the cutting angles of the disk gangs, and flexible suspenders connected with the bearings at the inner ends of the axles for vertically inclining each disk gang relatively to the land and maintaining it in its inclined position. 110 115 120

4. A disk harrow comprising a center frame, a plurality of disk gangs arranged in groups and connected with the frame, means for adjusting the cutting angles of each group of disk gangs, and means for vertically inclining each disk gang relatively to the land and maintaining it in an inclined position, having one group of disk gangs connected 125 130

to the center frame for undulating with it and the other group connected to the center frame for undulating independently of it.

5. A disk harrow comprising a center frame, a plurality of disk gangs arranged in groups and connected with the frame, means for adjusting the cutting angles of each group of disk gangs, and means for vertically inclining each disk gang relatively to the land and maintaining it in an inclined position, having one group of disk gangs connected to the center frame for undulating with it and the other group connected to the center frame for undulating independently of it, 15 and means for maintaining the spaced relation of the last mentioned group to the first mentioned group and permitting of its undulations.

Dated at Elora this twenty-first day of August, 1930.

TIMOTHY CLARK WARDLEY.
